UNITED STATES PATENT OFFICE.

ANISE F. FRAME, OF SOUTH CHARLESTON, WEST VIRGINIA, ASSIGNOR OF ONE-HALF
TO WILLIAM NEELEY, OF SOUTH CHARLESTON, WEST VIRGINIA.

SAFETY SWINGING SCAFFOLD.

Application filed July 3, 1922. Serial No. 572,645.

To all whom it may concern:

Be it known that ANISE F. FRAME, a citizen of the United States of America, residing at South Charleston, in the county of 5 Kanawha and State of West Virginia, has invented certain new and useful Improvements in Safety Swinging Scaffolds, of which the following is a specification.

This invention relates generally to scaffolds 10 supports and particularly to a construction in which provision is made, not only for supporting the platform of the scaffold, but also for elevating and lowering the same.

One of the particular features of the invention resides in a construction which permits of the operation of the elevating and lowering mechanism either by manual or 15 automatic means, which later, specifically, 20 may consist of a small electric motor.

A further feature resides in a construction in which the ratio of the gears of the operating mechanism is such that the scaffold, even under excessive load due to the weight 25 of the material and the workmen on the platform, may easily be elevated when occasion requires.

A further feature resides in a construction which permits the use of greater space on 30 the platform for workmen and materials, by the arrangement of the operating mechanism entirely beneath said platform.

Further features reside in the novel and specific construction and arrangement of 35 parts which results in maximum efficiency of operation of the apparatus.

In the accompanying drawings,

Figure 1 is a top plan view of the wall of a building and showing the relation of my 40 scaffold thereto;

Figure 2 is a top plan view of one of the platform supporting and elevating and lowering frames;

Figure 3 is a longitudinal vertical sectional view on the line 3-3 of Figure 2,

Figure 4 is a longitudinal vertical section on the line 4-4 of Figure 1,

Figure 5 is a transverse vertical section on the line 5-5 of Figure 2, and,

Figure 6 is a similar sectional view on the line 6-6 of Figure 2.

Referring more specifically to the drawings by numerals of reference, 2 indicates a building wall of conventional type, the 55 front vertical face is shown at 3, and 4, the

platform of a scaffold with which my supporting mechanism is associated.

The platform supporting, and elevating and lowering mechanisms of which there are of course two, one for each end of the platform, are shown more clearly in Figures 2 60 and 3, and as the construction of one is identical with the other, a description of one will suffice.

Horizontally arranged beneath the platform which it supports, and perpendicular to the plane of the wall face 3, and at each end of said platform, is a rectangular oblong frame 6, embodying lateral beams or bars 8 held in spaced parallel relation thru a plurality of transverse metal bars 9, the ends of which are turned at right angles from the plane of the body as at 10 and suitably and rigidly secured to the inner faces of the parallel beams 8. The transverse bars 70 9 and 9¹ of which there are four in number, are arranged in pairs toward each end of the frame 6, said bars constituting, in addition to their function of supporting and bracing the lateral beams, a means in which 75 are journaled certain of the operating elements presently to be described.

Journaled at its ends in each pair of transverse bars 9, 9¹, and preferably to one 80 side of the longitudinal axis of the frame 6, is a rotary shaft 11 having keyed or otherwise fixed thereon, a winding spool or drum 12, and intermediate said spool and the adjacent face of the bar 9¹, a ratchet wheel 14, 85 also fixed on the shaft 11.

Each shaft extends inwardly thru its supporting bar 9¹, and the extension 15 has keyed or otherwise fixed thereon a spur gear 16 which meshes with a relatively smaller spur gear 21 at each end of a longitudinal 90 rotary shaft 18 also journaled at its ends in the transverse bars 9¹.

Arranged transversely of the frame intermediate the bars 9¹, and journaled at its ends in the parallel lateral beams 8, is a 100 rotary drive or power shaft 19 formed at one end into a worm 20 which is in gear with a worm wheel 22 on and fixed for rotation with the longitudinal shaft 18. Adjacent its other end, the power shaft 19 has keyed thereon a sleeve 23 having a spur gear 24 which is in mesh with a relatively smaller pinion 25 on the shaft 26 of an electric motor 28 supported by a bracket 29 on the inner face of one of the lateral beams 8. 110

An extension 30 of the shaft 19 which projects thru one of the beams 8, carries a ratchet wheel 32 which is rotated with a step-by-step movement thru the medium of a manually operated lever 33 journaled on the extension of said shaft, a pawl 34 pivoted thereon co-operating with the teeth of said ratchet wheel.

The platform and its supporting and elevating and lowering mechanism is suspended by cables 36 from suitable means on the roof of the building or beams which extend laterally beyond the face of the wall thereof, said cables being wrapped around the winding drums or spools 12 and fastened at one end thereto.

For the purpose of locking the winding drums against rotation and thus preventing the platform to descend under its weight and that of the workmen and materials thereon, I provide a rocking bar 38 secured by straps 39 to the inner face of one of the lateral beams and provided with arms 40 on the ends thereof and at right angles thereto, said arms terminating in pawls 42 which co-operate with the teeth of the ratchet wheels 14. The platform 4 is provided with apertures 44 thru which pass the elevating and lowering cables 36 and an aperture 46 thru which extends the handle of the operating lever 33, the latter being manually actuated to cause the drums to be rotated in a direction to wind the cables thereon. The rocking bar is operated by a handle 48 to release the pawls 42 from engagement with the ratchet wheels 14, and is accessible thru an opening 50 in the platform 4. Whenever it is desired to lower the platform, the locking pawls are disengaged from the ratchet wheels 14 and by gravity the platform will be caused to descend in a manner as is obvious from the construction shown. The winding cables will be caused to rotate in the reverse direction when the platform is lowered.

What I claim and desire to protect by Letters Patent is:

1. In an elevating and lowering mechanism for scaffolds, a frame comprising spaced parallel beams and transverse bars

arranged in pairs therebetween, winding drums journaled between the pairs of transverse bars, a ratchet associated with the inner face of each winding drum, a gear having connection with the shaft of each drum, a longitudinal driven shaft supported between the inner pair of transverse bars, gear wheels carried at the ends thereof meshing with the last mentioned gears, a drive shaft disposed transversely of said beams and having connection with said driven shaft, means for rotating said drive shaft, and a rocking bar journaled on one of the beams of said frame and provided at its ends with transversely disposed pawls cooperating with the aforesaid ratchets on said drums for limiting the movement of the latter in one direction, and means for manually actuating said rocking bar.

2. In an elevating and lowering mechanism for scaffolds, a frame comprising spaced parallel beams and transverse bars arranged in pairs therebetween, winding drums journaled between the pairs of transverse bars, a ratchet associated with the inner face of each winding drum, a gear having connection with the shaft of each drum, a longitudinal driven shaft supported between the inner pair of transverse bars, gear wheels carried at the ends thereof meshing with the last mentioned gears, a drive shaft disposed transversely of said beams and having connection with said driven shaft, means for rotating said drive shaft, a rocking bar journaled on one of the beams of said frame and projecting through the inner pair of transverse bars, laterally disposed pawls carried at the ends of said rocking bar and adapted normally for engagement with the aforesaid ratchets on said drums to lock the latter against rotation in one direction, and a lever carried on said rocking bar intermediate of its ends and adapted for manual actuation, whereby to rock said bar and release the pawls from engagement with said ratchets.

In testimony whereof I affix my signature.

ANISE F. FRAME.
